WILLIAM C. STEINHORST AND HENRY O. STEINHORST, OF UTICA, NEW YORK, ASSIGNORS TO EMIL STEINHORST & SONS, INC., OF UTICA, NEW YORK, A CORPORATION

FURNACE

Application filed March 14, 1929. Serial No. 347,114.

This invention relates to warm air furnaces and is particularly designed for such furnaces using fluid fuel, that is gas or oil fuel.

The purpose of this invention is to provide a warm air furnace of the fluid fuel type of new and improved construction and of a form which is economical and simple to manufacture and efficient and durable in use. A further purpose is to provide a fluid fuel burning and warm air heating furnace where the parts are so constructed, combined and co-ordinated as to be adapted to transfer a very high percentage of heat from the burning fuel to the air to be warmed by the furnace.

15 A further object of the invention is to provide in a furnace of the class described a construction where the flues, meaning thereby the flue headers and flue pipes hereinafter described in detail, are so constructed that they may be assembled in larger or smaller units and such units thereafter assembled upon or adjacent to the combustion chamber; and further to provide a construction where- 20 in the said flues are adapted to be conveniently supported within the casing of the furnace and accessible for internal cleaning of the flues without removing the casing; and fur- 25 ther to have the ends of said flues that are 30 adjacent the casing detachably mounted on or secured to said casing and to have regis- 35 tering holes in the flue ends and the casing so that said clean-out apertures may be nor- 40 mally closed by caps placed upon the furnace 45 from without the casing. Further purposes 50 and advantages of the invention will appear 55 from the specification and claims herein.

Fig. 1 is a perspective view of a warm air furnace embodying this invention.

40 Fig. 2 is a similar perspective view of said furnace but with most of the casing removed, but with a vent pipe or smoke pipe still attached to the furnace.

45 Fig. 3 is a horizontal sectional view partly on a horizontal line just below the top of the combustion chamber and with the farther half of the furnace shown on the slanting plane of the lower series of flues.

50 Fig. 4 is a vertical sectional view of part

of the furnace on line 4—4 of Fig. 3 on an enlarged scale.

Referring to the drawings in a more particular description, it will be seen that this furnace comprises a combustion chamber 10, fluid fuel burners 11 located in the lower part thereof and a system of flues generally denoted by the numeral 12, leading from opposite sides of the combustion chamber downwardly in a zigzag direction but generally parallel to the sides of the combustion chamber and opening into the vent or smoke pipe 13. Around and over this combustion chamber and system of flues is placed the casing, generally denoted by the numeral 14, and arranged to conduct the incoming cold air from the inlet 15 upwardly close to the combustion chamber and close to and in repeated or successive contact with the flue headers and flue pipes to the upper part of the casing from which the air is conducted by ordinary warm air conduits 16.

The combustion chamber 10 is conveniently formed out of sheet metal so as to be preferably roughly rectangular in shape, so that the combustion chamber is higher and longer than the width of the chamber, resulting in having two relatively long high opposite sides 17, front and back ends 18 and 19 respectively, bottom 20 and a top 21.

This combustion chamber will be suitably supported above the base 22 as by a plurality of legs 23. In the bottom of the combustion chamber are placed the desired number and type of fluid fuel burners 11. In the drawings two such burners adapted for burning gas are shown and these burners are supplied by gas through pipes 50 leading outwardly from the combustion chamber through a vestibule 24 to a point without the casing where said pipes are connected to the main gas supply pipe 25 provided with valves and regulating apparatus, the details of which need not be described here.

In order to afford greater surface for radiation of heat from the sides of the combustion chamber and for greater area to be engaged by the ascending current of air to be heated, the greater part, say the forward three fourth or four fifths of the wide, high

sides 17, are provided with decided or pronounced corrugations so that in horizontal cross section the material of said sides has the shape shown particularly in Fig. 3, consisting of V-shaped projections 26 closely spaced along the said side.

Towards the top of the combustion chamber 10 and in the embodiment of the invention shown in Figs. 1-3, towards the rear 10 end of the combustion chamber there is located on each side of the chamber an upper flue header 27. This header consists of a short tubular branch 28 extending outwardly from the side 17 of the combustion chamber 18 to the main longitudinally extending portion 29 of said header, which main portion 29 will preferably be formed circular in shape and slanting to be smaller at its rear end than at its forward end 30. The rear end of this 20 upper header is preferably open for its full diameter. Said rear end of the header projects rearwardly into line with the back 31 of the casing 14. This open end of the header 27 is normally closed by a removable 25 or detachable cap 32 applied from without the said casing so as to cover the open rear end of said header, it being understood that the rear 31 of the casing is cut away for the extent of the diameter of the rear opening 30 of the header. The cap 32 is removably held in place as by thumb nuts 33 placed at the outer surface of the cap and engaging the forward screw-threaded ends of short rods 34 secured to the opposite sides of the body 35 of the header 27 and projecting rearwardly through small holes conveniently formed in the rear 31 of the casing, and through aligned holes in the cap 32 near its periphery.

It will be understood that the portion of 40 the side 17 of the combustion chamber opposite the tubular branches 28 of these two headers are cut away so that free communication is given from the inside of the combustion chamber to said header.

45 From the upper flue header 27 on each side of the combustion chamber the products of combustion are led forwardly and downwardly through a plurality of forwardly extending and downwardly slanting flue pipes 35. The forward ends of each upper series of flue pipes are connected to the upper half of the rearward face 36 of the front or intermediate flue headers 37 on that side of the combustion chamber.

55 These front flue headers are conveniently shaped to be in the form of a truncated cone with the small end thereof towards the front of the furnace. Said forward end of this header is open and is in the plane of the 60 front 38 of the casing, which casing is cut away opposite said front open end of the header. Upon the opposite sides of this header 37 are forwardly projecting screw-threaded rods 39 projecting through the front 65 38 of the casing. By means of these rods

and thumb screws 41 the front caps 40 are removably held in place to normally close the front end of these flue headers.

From the lower half of the rear face or end 36 of these intermediate headers 37 there are provided and connected a second series of flue pipes 42 which extend rearwardly and slant downwardly being spaced from the adjacent side 17 of the combustion chamber and substantially parallel therewith. The rear and lower ends of the pipes in this second series 42 are connected to the front larger end 43 of a third or lower rear flue header 44. The body of this header is preferably formed to taper towards its rear end 45 and said rear end projects out through a suitable hole cut in the rear 31 of the casing. The said projecting rear ends 45 of the two headers 44 are connected to the branch vent pipes 13a which soon unite into the main vent pipe 13 leading to the stack or chimney (not shown).

It will be seen that the system 12 of flues on each side of the combustion chamber may be conveniently assembled as a unit consisting of the upper rear flue header 27, upper series of flue pipes 35, front flue header 37 and rear or second series of flue pipes 42 and lower rear header 44. Each said side system of flues will then be readily connected to the combustion chamber by connecting the inner end of the short tubular branch 28 of the upper flue header 27 to its side of the combustion chamber. Each forward flue header 37 is supported by resting on an arm 47 secured to the front of the combustion chamber and extending beneath a flat-bottomed boss 48 on the flue header but with said arm not fastened to the boss whereby the header is supported independently of the casing but some slight relative movement between the arm and header is permitted as the parts of the furnace expand and contract. An arm 49 projects from the rear of the combustion chamber beneath each rear lower header 44 to similarly support this header and the parts attached thereto independently of the casing.

A little below the openings from the combustion chamber into the upper rear flue headers 27 there is placed and fixedly supported in position within the combustion chamber a baffle plate 46. This baffle plate extends from the back end 19 of the combustion chamber forwardly substantially on a horizontal plane nearly to the front end 18 of the combustion chamber. This baffle plate operates to hold the gases from combustion for an appreciable time within the part of the combustion chamber below the baffle plate, but to allow said products of combustion to pass upwardly past the front end of the baffle towards the front end of the combustion chamber. From this point the products of combustion move rearwardly towards the rear of the combustion chamber and then pass

from the combustion chamber laterally in opposite direction to the oppositely placed rear upper headers 27. Preferably the baffle plate 46 is rectangular in form and has straight edges at its sides so that it does not enter into the V-shaped corrugations 26 on the sides 17 of the combustion chamber. There is thus afforded a series of small triangular shaped openings 47 between the side edges of said baffle plate and the corrugated sides 17, and through this series of openings a small part of the products of combustion can pass directly upward to the upper side of the baffle plate. These small direct upwardly traveling currents tend to keep the products of combustion spread out within the combustion chamber below the baffle plate and also tend to thoroughly commingle the products of combustion again above the baffle plate, thus bringing as much heat as possible to the side walls of the combustion chamber. From each upper rear header 27 the products of combustion are separated into several small currents passing forwardly and downwardly through the first series of flue pipes 35. These flue pipes are of relatively small diameter and are parallel with the side walls 17 of the combustion chamber. On account of the small size of these flue pipes 35 the products of combustion are afforded an opportunity to give up their heat to the relatively large area of the said pipes to the air which ascends in the furnace between the side walls 17 of the combustion chamber and the closely adjacent side walls of the casing. After the products of combustion reach the forward flue headers 37 the different currents from the first series of flue pipes 35 are united and commingled and then are again separated into the several pipes of the lower series 42 of flue pipes. Here in these pipes again a free opportunity is afforded for the products of combustion to yield up their heat through the relatively large area of the flue pipes 42 to the ascending current of air to be warmed. By the time the gas products of combustion reach the lower series 42 of flue pipes their heat is reduced but still high and adapted to give a first or preliminary heating to the air passing upwardly around and past these flue pipes 42. The air thus heated then is brought into engagement with the hotter flue pipes 35 and thus given a greater degree of temperature. Preferably in both upper series 35 and lower series 42 of flue pipes the pipes in each series will be staggered and offset so as to more completely fill the space between the side 17 of the combustion chamber and the adjacent side of the casing and cause the ascending air to be diverted in its direction two or three times as it passes said flue pipes. In other words the upper pipes of the series 42 will be offset relative to the lower pipes of that series so that air coming up between the two lower pipes will be brought

directly against one of the pipes in the upper half of this series.

The space between the back 19 of the combustion chamber and the back 31 of the casing is restricted so as to allow relatively little air to pass upwardly at this point, and so divert most of the air to the sides of the combustion chamber. However, the air passing upwardly at the rear of the combustion chamber is heated by contact with and radiation from the back 19 of said combustion chamber. The upper rear flue headers 27 and the lower rear flue headers 44 occupy a large portion of the cross area at the two rear corners of the casing and so retard the upward current of air at those two points sufficiently to allow the air passing by said flue headers to absorb the heat from said flue headers, the upper one of which particularly is at the highest temperature of any of the flue system.

At the front of the combustion chamber the vestibule 24 obstructs the direct ascent of air directly in front of the combustion chamber and thus diverts the air to the two sides. Above the level of this vestibule however the ascending air is heated by contact with and radiation from the front end 18 of the combustion chamber and at the two front corners of the casing by contact with the extended surfaces of the two intermediate headers 37.

It will now be seen that this invention provides a simple form of warm air furnace of the fluid fuel burning type and one that is particularly simple in construction as far as the combustion chamber and flues are concerned, and yet has such combustion chamber and flues so arranged and combined as to absorb or extract a very large percentage of the heat from the products of combustion and thus obtain a fluid fuel furnace which is commercially economical in operation notwithstanding the relatively high cost of the fuel used in the furnace.

Furthermore it will be noticed that notwithstanding the relatively large area of flues and the number of flue pipes and flue headers used, all of the parts of the flue system are accessible for cleaning by simply removing the removable caps 32 and 40 from the outer side of the casings and without having to dismantle the furnace at all or remove any of the casing. Similarly access if desired to the lower rear flue header 44 may be readily had through disconnecting the vent pipe 13 from the projecting ends 45 of said rear lower flue headers.

What is claimed and it is desired to secure by Letters Patent is:

1. In a warm air furnace, the combination of an outer casing, a combustion chamber extending from near the base of the casing to near the top of the casing, and having its side walls vertically corrugated, fluid-fuel burners in the lower part of the combustion chamber, flues within the casing and com-

municating with the side of said combustion chamber near its upper part and slanting continuously downwardly in a zig-zag course towards one end of the chamber and spaced from and parallel with the said side of said chamber, a vent pipe leading from the lower end of said flues to the chimney, an inlet for cold air near the base of the casing and means connected to the upper part of the 10 casing for conducting the warm air from the furnace.

2. In a warm air furnace, the combination of an outer casing, a combustion chamber extending from near the base of the casing to 15 near the top of the casing and having its side walls vertically corrugated, fluid-fuel burners in the lower part of the combustion chamber, flues within the casing and communicating with one side of said combustion chamber near 20 its upper part near one end and slanting continuously downwardly towards the other end of the combustion chamber and spaced therefrom and parallel with the said side of said chamber and then returning in a continuously downward slanting direction towards 25 the first mentioned end of the chamber and still spaced therefrom and parallel with the said side of said chamber, a vent pipe leading from the lower end of said flues to the chimney, an inlet for cold air near the base of the casing and means connected to the upper part of the casing for conducting the warm air from the furnace.

3. In a warm air furnace, the combination 30 of an outer casing a combustion chamber extending from near the base of the casing to near the top of the casing, fluid-fuel burners in the lower part of the combustion chamber, flues within the casing and communicating 35 with one side of said combustion chamber near its upper part near one end and slanting continuously downwardly towards the other end of the combustion chamber and parallel with said side and spaced therefrom 40 and then returning towards the first mentioned end of the chamber and still parallel with said side and spaced therefrom and slanting downwardly, a vent pipe leading from the lower end of said flues to the chimney, an inlet for cold air near the base of the 45 casing and means connected to the upper part of the casing for conducting the warm air from the furnace.

4. In a warm air furnace, the combination 50 of an outer casing a combustion chamber extending from near the base of the casing to near the top of the casing, fluid-fuel burners in the lower part of the combustion chamber, flues within the casing and on the opposite 55 sides of the combustion chamber and communicating with said combustion chamber near its upper part near one end and slanting downwardly and on opposite sides thereof towards the other end of the combustion chamber and spaced therefrom and parallel with 60

said sides and then returning towards the first end of the chamber and still spaced therefrom and parallel to said sides and slanting downwardly, a vent pipe leading from the lower end of said flues to the chimney, an inlet for cold air near the base of the casing and means connected to the upper part of the casing for conducting the warm air from the furnace. 70

5. In a warm air furnace, the combination 75 of an outer casing a combustion chamber extending from near the base of the casing to near the top of the casing and having its side walls vertically corrugated, fluid-fuel burners in the lower part of the combustion chamber, flues within the casing and on the opposite sides of the combustion chamber and 80 communicating with said combustion chamber near its upper part near one end and slanting continuously downwardly and on opposite sides thereof in a zig-zag course towards one end of the chamber and spaced therefrom and parallel with said sides, a vent pipe leading from the lower end of said flues to the chimney, an inlet for cold air near the 85 base of the casing and means connected to the upper part of the casing for conducting the warm air from the furnace. 90

6. In a warm air furnace the combination 95 of an outer casing a combustion chamber extending from near the base of the casing to near the top of the casing, and having its side walls vertically corrugated, fluid-fuel burners in the lower part of the chamber, a flue header communicating with one broad side 100 of said combustion chamber near its upper part near one end thereof and projecting outwardly therefrom, a plurality of flue pipes in staggered arrangement extending from said header in a slanting direction towards the other end of the chamber and spaced therefrom and from each other and parallel to the said broad side of said chamber, a second series of flue pipes in staggered arrangement 105 below said first series and slanting downwardly towards the first end of the chamber and parallel with said side, a second header connecting the lower ends of the upper series of pipes with the upper ends of the lower series of pipes, a third header into 110 which lead the lower ends of the lower series of pipes, a vent pipe leading from said third header to the chimney, said casing surrounding said combustion chamber, headers and flue pipes, an inlet for cold air near the base 115 of the casing and means connected to the upper part of the casing for conducting the warm air from the furnace. 120

7. In a warm air furnace the combination 125 of an outer casing a combustion chamber extending from near the base of the casing to near the top of the casing, and having its side walls vertically corrugated, fluid-fuel burners in the lower part of the chamber, a flue header on each opposite side of said 130

chamber communicating with said combustion chamber near its upper part and projecting outwardly therefrom, a plurality of flue pipes in staggered arrangement extending from each of said headers in a downwardly slanting direction towards one end of the chamber and spaced therefrom and from each other and parallel with said sides of the combustion chamber, a second series of flue pipes in staggered arrangement on each side below said first series and slanting downwardly towards the opposite end of the chamber parallel with said sides, a second header on each side connecting the lower ends of the upper series of pipes with the upper ends of the lower series of pipes, a third header on each side into which lead the lower ends of the lower series of pipes, a vent pipe leading from said third headers to the chimney, said casing surrounding said combustion chamber, headers and flue pipes, an inlet for cold air near the base of the casing and means connected to the upper part of the casing for conducting the warm air from the furnace.

25 8. In a warm air furnace the combination of an outer casing a combustion chamber extending from near the base of the casing to near the top of the casing, and having its side walls vertically corrugated, fluid-fuel burners in the lower part of the chamber, a flue header on each opposite side of said chamber communicating with said combustion chamber near its upper part and projecting outwardly therefrom, a plurality of flue pipes extending from each of said headers in a slanting direction towards one end of the chamber and spaced therefrom and from each other and parallel with said sides of the combustion chamber, a second series of flue pipes on each side below said first series and slanting downwardly towards the opposite end of the chamber parallel with said sides, a second header on each side connecting the lower ends of the upper series of pipes with the upper ends of the lower series of pipes, a third header on each side into which lead the lower ends of the lower series of pipes, a vent pipe leading from said third headers to the chimney, said casing surrounding said combustion chamber, headers and flue pipes, an inlet for cold air near the base of the casing, means connected to the upper part of the casing for conducting the warm air from the furnace, and detachable caps on the open outer ends of said first and second named headers which caps are removable and replaceable from without the casing whereby said headers and their attached flue pipes are accessible for cleaning.

60 In witness whereof we have affixed our signatures, this 26th day of February, 1929.

WILLIAM C. STEINHORST.
HENRY O. STEINHORST.
